ROAD MACHINE

John F. Henry, Staples, Minn.

Application February 11, 1941, Serial No. 378,451

6 Claims. (Cl. 262—2)

This invention relates to road machines, and has for one of its objects the production of an efficient machine for facilitating the removal of sod, stones, and other foreign or undesirable materials from the surface of a road, and placing such materials upon a suitable conveyance for removal or transfer to a desired location.

A further object of this invention is the production of an efficient mechanism for lifting material from the surface of a road, then moving the material longitudinally of the road machine, and then dumping said material upon a suitable conveyor.

Other objects and advantages of the present invention will appear throughout the following specification and claims.

In the drawings:

Figure 1 is a side elevational view of the machine;

Figure 2 is a top plan view;

Figure 3 is a longitudinal sectional view taken on line 3—3 of Figure 2;

Figure 4 is a top plan view of the chassis with certain parts of the machine removed;

Figure 5 is a vertical sectional view taken on line 5—5 of Figure 3;

Figure 6 is a vertical sectional view taken on line 6—6 of Figure 3, certain parts being removed;

Figure 7 is a detached fragmentary perspective view of the spiral conveyor member;

Figure 8 is an enlarged top plan view of one of the clutches;

Figure 9 is a fragmentary side elevational view of a portion of the rear end of the screening drum.

By referring to the drawings, it will be seen that 15 designates the main frame which is preferably rectangular in shape and is provided with a forwardly extending downwardly inclined cutting blade supporting portion 16. This portion 16 converges towards the longitudinal center of the machine and supports the downwardly inclined cutting blade 17, this blade 17 being of less width than the frame 15, as shown in Figures 2 and 4. The forward lower end of the cutting blade 17 carries a steel shoe 18 to reinforce the forward lower end of the cutting blade 17. The frame 15 is preferably of a channel iron or I-beam structure in cross section to strengthen the frame or chassis. A substantially U-shaped tractor hook-up or tongue 19 is carried by the forward end of the portion 16 and is provided with wings 20 which are slotted to receive the forward ends 21 of the flanges 22 of the portion 16 to provide a firm connection and brace. These

wings 20 are riveted or otherwise secured to the portion 16. Suitable apertures 23 are formed in the tongue 19 to facilitate the attachment of a tractor hitch.

5 An endless conveyor 24 is carried by sprockets and shaft assemblies 25 and 26 mounted at opposite ends of the conveyor frame 27, which frame 27 may be supported by any desired means and is inclined upwardly and rearwardly from the inner end of the cutting blade 17, as shown in Figure 3. Wheels 28 support the frame 15, as shown in Figures 1 to 4, and the conveyor 24 is driven by a suitable chain 29^a and sprockets 29^b. The sprockets 29^b are carried by a shaft 29^c, which in turn is driven by the main drive chains 29. These chains 29 are driven from the sprockets 30 carried by the axle 28^a, which axle 28^a is supported by the wheels 28. The conveyor 24 is driven in the direction of the arrows shown in Figure 3 when the machine travels forwardly. The chains 29 also pass over idle guiding sprockets 30 carried by the frame 15, as shown in Figures 1, 2, 3 and 4.

20 A lift reel 31 is journaled above the tongue 19, as shown, and is carried by the rearwardly extending braces 32. The braces 32 are carried or hung at their rear ends upon the transverse shaft 33. The shaft 33 is driven by the chain assembly 29. This shaft 33 drives a chain 34 which in turn drives the lift reel 31 in the direction of the arrows in Figure 3. The lift reel 31 carries a plurality of radiating blades 35 which are so positioned as to force material cut by the cutting blade 17 toward the forward end of the conveyor 24 where this material may be elevated to the screening drum 36.

25 The shafts 33 and 29^c are provided with suitable slip clutch elements 37 to relieve the load pull on the shafts in the event that the shafts should be subjected to unexpected strain or unusual load. These slip clutches may be located upon any of the driving shafts without departing from the spirit of the invention and preferably comprise a structure such as is illustrated in detail in Figure 8, wherein a loosely mounted collar 39 is carried by the supporting shaft for example, the shaft 33, the collar 37 being secured to or forming a part of the adjoining sprocket wheel. A clutch collar 40 is keyed to the shaft 33 to rotate therewith and to slide longitudinally thereof, the collar 40 being yieldably held in contact with the collar 39 by means of a coil spring 41 the tension of which may be adjusted by an adjustable collar 42 held in a set position upon the shaft 33 by a set screw 43.

As stated above, this structure as illustrated in Figure 8 provides a spring-pressed slip clutch which may be adjusted to the desired load, and these clutches may be located upon any of the power shafts, it being thought necessary only to specifically describe one example.

As shown in Figures 1, 2, and 3, the screening drum 36 is mounted to extend longitudinally of the rear end of the frame 15 and preferably comprises an elongated hollow wire screen cylinder. This drum 36 is provided with suitable end rings 44, one ring being located at each end of the screening drum 36, these end rings 44 being of a channel iron structure having concave outer channels 45. A central ring 46 similar to the rings 44, is carried by the drum 36, as shown. Annular end bands 47 are placed at each end of the drum to partially overhang the forward and rear edges of the drum 36, as shown, and to retard the outflow of screening material from the bottom of the drum as the drum rotates. These bands 47 are preferably narrow and extend inwardly of the inner face of the drum 36 for only a short distance. In view of the fact that the accumulated material in the bottom of the drum does not very often extend to a great height within the drum.

A power shaft 48 obtaining power from a forward tractor or other suitable means extends rearwardly from the frame 15 and this shaft 48 carries a plurality of rubber tired rollers 49 which are so positioned as to place the treads of these rubber-tired rollers 49 in the channels of the rings 44 and 46, and frictionally contact therewith for the purpose of rotating the drum 36 as the shaft 48 and rollers 49 are rotated. An auxiliary shaft 50 is carried by the frame 15 in parallel relation to the shaft 48 and upon the opposite side of the center of the frame 15, as shown in Figure 4. Rollers 51 similar to the rollers 49 are carried by the shaft 50 and these rollers travel in the channels of the rings 44 and 46 for providing proper traction to rotate the drum 36. The shafts 48 and 50 are connected by means of a sprocket chain 52 for rotating the shafts 48 and 50 in unison.

In order to brace the drum 36 against forward shifting movement, I provide a pair of forwardly and upwardly inclined braces 52 upon opposite sides of the drum 36, which braces are anchored to the frame 15, as shown in Figure 5, and carry a transverse shaft 53 at their upper ends. This shaft 53 carries friction rollers 54 which abut the outer face of the forward ring 47, as shown in Figures 3 and 5. A pair of similar braces 55 are carried near the rear end of the frame 15 and are inclined upwardly and rearwardly. These braces 55 carry a shaft 56 which extends transversely across the rear of the drum 36 and supports friction rollers 57 which contact with the rear face of the rear band 47, as shown in detail in Figure 9. Additional rollers 58 are carried by the braces 55 to contact the sides of the rear rings 44 to resist lateral sway of the drum 36.

A tray 59 is fixed upon the shaft 56, and this tray 59 is mounted to extend approximately one-half of its length into the rear of the drum 36, and the other half beyond the rear end of the drum 36, as shown in Figures 3 and 9. A crank arm 60 is carried by the shaft 56 and this crank arm 60 is connected to a pull rod 61 extending to a suitable and convenient place for control by the operator to permit of the proper angular adjustment of the tray 59. By shifting the rod 61 in the desired direction it will be seen that the

tilting tray 59 may be swung in the arc of a circle, indicated in dotted lines in Figure 9.

A spiral conveyor element 62 is carried within the drum 36 and follows closely the inner face of the wire mesh screening, the spiral conveyor element 62 extending from the forward toward the rear end of the drum 36, as shown in Figure 3. This spiral conveyor 62 is provided with a toothed inner edge 63, as shown in detail in Figures 5 and 6. Suitable shelves 64 are carried by the spiral conveyor 62 at desired locations within the length thereof, as shown in Figures 6 and 7, to facilitate the lifting of the material as the drum rotates.

The operation of the machine is as follows: The machine travels forwardly, being drawn by a tractor or other propelling means, and as the machine travels forwardly the supporting wheels 28 are imparting driving movement to the chain 29 which in turn will cause the lift reel 31 to rotate in the direction of the arrow shown in Figure 3 forcing material scraped up by the cutting blade 17 upwardly toward the forward end of the endless conveyor 24 where the material will be elevated and delivered into the forward end of the drum 36. The drum 36 at the same time will be rotated by the friction rollers 49 and 51, and the forward movement of the drum 36 will be resisted by the rollers 54. As the drum 36 continues to rotate the spiral conveyor element 62 which is inclined rearwardly will convey the material toward the rear end of the drum 36, and as the drum 36 rotates the fine material will be screened or dropped through the drum 36 upon the floor of the road. The tilting tray 59 is properly adjusted to cause the material lifted at the rear end of the drum 36 to drop upon the tray, which tray when properly adjusted will shoot this heavy material dropped thereon into a truck or other conveyance A, shown in dotted lines in Figure 3 in the rear of the drum 36. If the material is not sufficiently screened, however, the tray 59 may be swung in the direction of the arrow adjacent the tray 59 to cause the tray to tilt inwardly of the drum and prevent material from being delivered outwardly of the drum until properly screened.

It should be understood that the present device is particularly adaptable for use in building roads and the like, or the removal of sod and delivering the sod to a conveyance or other means adapted to receive said material. It should be understood that the cutting blade 17 may be of suitable or varied shape depending upon the character of work to be performed and the conveyor 24 may be mounted at a desired angle, depending upon the nature of the work and the kinds of materials to be handled and other conditions affecting the work. The conveyor may be of suitable material, such as rubber or a metallic elevator apron may be used. Suitable chain tighteners and other suitable mechanism may be employed to facilitate operation and other detail mechanical features may be modified without departing from the spirit of the invention so long as such changes fall within the scope of the appended claims.

It should be understood that the shaft which supports the reel 31 normally rests upon the tongue 19 as it appears in Figure 1, but should the reel come into contact with a large stone or other hard material, the lifting strain on the fins of the reel would cause the reel and the supporting arms 32 to be moved upwardly due to the fact that the connection of the arms 32 with the shaft 33 provides a hinging connection. The tongue 19

however, will constitute means for limiting the downward movement and indicates the maximum lowermost position of the reel 31.

What is claimed as new is:

1. A machine of the class described comprising a frame, said frame having an integral forwardly and downwardly projecting portion at the front thereof, a cutting blade supported at the forward end of the frame, an endless conveyor supported upon the frame and being inclined upwardly and rearwardly of the frame, means for driving the conveyor, a lift reel supported forwardly of the cutting blade for moving material toward the conveyor as material is cut by the cutting blade, a screening drum carried by the frame in the rear of the conveyor and positioned to receive material from the conveyor, means for rotating said screening drum, a brace connected to the frame and to the lift reel for bracing the same, a tongue extending forwardly of the front end of the frame, said tongue having rearwardly extending portions terminating in wings, and the wings having notches for receiving portions of the frame to brace the tongue.

2. A machine of the class described comprising a frame, said frame having an integral forwardly and downwardly projecting portion at the front thereof, a cutting blade supported at the forward end of the frame, an endless conveyor supported upon the frame and being inclined upwardly and rearwardly of the frame, means for driving the conveyor, a lift reel supported forwardly of the cutting blade for moving material toward the conveyor as material is cut by the cutting blade, a screening drum carried by the frame in the rear of the conveyor and positioned to receive material from the conveyor, a pair of driving shafts mounted upon opposite sides of the frame and extending longitudinally thereof, traction rollers carried by the shafts, channel bands carried by the drum for receiving the rollers for rotating the drum as the rollers are rotated, and bracing means spanning the forward and rear ends of the drum for holding the drum against longitudinal movement upon the frame.

3. A machine of the class described comprising a frame, said frame having an integral forwardly and downwardly projecting portion at the front thereof, a cutting blade supported at the forward end of the frame, an endless conveyor supported upon the frame and being inclined upwardly and rearwardly of the frame, means for driving the conveyor, a lift reel supported forwardly of the cutting blade for moving material toward the conveyor as material is cut by the cutting blade, a screening drum carried by the frame in the rear of the conveyor and positioned to receive material from the conveyor, a pair of driving shafts mounted upon opposite sides of the frame and extending longitudinally thereof, traction rollers carried by the shafts, channel bands carried by the drum for receiving the rollers for rotating the drum as the rollers are rotated, bracing means spanning the forward and rear ends of the drum for holding the arm against longitudinal movement upon the frame, said

5
bracing means comprising bracing arms, said bracing arms carrying transverse shafts, said transverse shafts carrying rollers and said drum having end bands overlying the edges of the drum, and said last mentioned rollers engaging said bands.

10
15
20
25
4. A machine of the class described comprising a frame, said frame having an integral forwardly and downwardly projection portion at the front thereof, a cutting blade supported at the forward end of the frame, an endless conveyor supported upon the frame and being inclined upwardly and rearwardly of the frame, means for driving the conveyor, a lift reel supported forwardly of the cutting blade for moving material toward the conveyor as material is cut by the cutting blade, a screening drum carried by the frame in the rear of the conveyor and positioned to receive material from the conveyor, means for rotating said screening drum, the means for driving said conveyor and lift reel comprising driving shafts and spring slip clutch means carried by each shaft to automatically relieve load from the driving means, said spring slip clutch means comprising an adjustable spring-pressed element to facilitate the manual regulation of the spring-pressed element.

30
35
40
45
5. A machine of the class described comprising a frame, excavating and lifting means carried by the forward end of the frame, a longitudinally extending substantially horizontally mounted screening drum carried by the frame in the rear of the lifting means for receiving material from the lifting means, said drum comprising a wire mesh substantially cylindrical body, means for rotating the drum, a spiral conveyor element extending spirally and longitudinally of the inner face of the drum for causing material to pass from the forward toward the rear end of the drum as the drum is rotated, teeth formed along the inner periphery of the spiral conveyor element, lifting plates carried by the spiral conveyor element at selected positions within the length of the spiral conveyor element, and retaining bands extending inwardly of the periphery of the drum to restrain material to be screened from falling out through the ends of the drum.

50
55
60
65
6. A machine of the class described comprising a frame, excavating and lifting means carried by the forward end of the frame, a longitudinally extending substantially horizontally mounted screening drum carried by the frame in the rear of the lifting means for receiving material from the lifting means, said drum comprising a wire mesh substantially cylindrical body, means for rotating the drum, a spiral conveyor element extending spirally and longitudinally of the inner face of the drum for causing material to pass from the forward toward the rear end of the drum as the drum is rotated, and a pivotally mounted tray carried at the rear end of the drum and extending partially within and partially without the drum, and means for swinging the tray to selectively cause material dumped upon the tray to fall into and out of the drum.

JOHN F. HENRY.
